COLLAPSIBLE BOAT

Marvin D. Wayne, Galesburg, Mich.

Application September 15, 1947, Serial No. 774,008

12 Claims. (Cl. 9—2)

1

This invention relates to improvements in collapsible boat.

The principal objects of this invention are:

First, to provide a novel form of collapsible boat which is extremely rigid and sea-worthy when erected and which may be collapsed to occupy a minimum of space.

Second, to provide a novel form of collapsible boat in which the several frame forming parts are flexibly connected to prevent their loss and to facilitate erection of the boat.

Third, to provide a novel shell or skin for a collapsible boat which is provided with integral longitudinal slats for stiffening the shell and the boat and which may be folded longitudinally and rolled transversely into a small bundle when collapsed.

Fourth, to provide a cover for a collapsible boat with sectional longitudinal stiffening members and foldable reinforcing flaps having slats arranged to bridge the space between the stiffening members in the cover when the cover is extended.

Fifth, to provide a framework for a collapsible boat in which the vertical ribs, including the stem and stern frame, are permanently connected together by flexible belting to prevent loss or misplacement of any of the ribs and to facilitate erection of the frame with the ribs in properly spaced relationship.

Sixth, to provide a framework for a collapsible boat with flexible connecting members arranged to locate the several parts of the framework in proper erected position and to receive sectional gunwale members for stiffening the gunwales of the boat.

Seventh, to provide a collapsible boat in which the main longitudinal stiffening members including the keel and gunwales are collapsible into short lengths so as to be conveniently packed and carried.

Other objects and advantages pertaining to the details and economies of my boat will be apparent from a consideration of the following description and claims. The drawings, of which there are three sheets, illustrate a preferred form of my boat.

Fig. 1 is a perspective view of my boat in erected position, portions being broken away to illustrate details of the framework and stiffening members.

Fig. 2 is a longitudinal cross sectional view through the framework of my boat in partially erected position.

Fig. 3 is a fragmentary perspective view of

2

the stern portion of the framework of my boat as viewed from the front of the boat.

Fig. 4 is a transverse cross sectional view along the line 4—4 in Fig. 1.

5 Fig. 4A is a fragmentary cross sectional view along the line 4A—4A in Fig. 1.

Fig. 5 is a fragmentary perspective view of the stern of my boat in erected position and partially broken away to show details of construction thereof.

Fig. 6 is an enlarged fragmentary perspective view of the inside of the shell of my boat and illustrating the arrangement of the longitudinal stiffening members on the shell.

10 Fig. 7 is a fragmentary perspective view of the forward portion of the framework of my boat in partially collapsed position.

Fig. 8 is a fragmentary perspective view of the connection between the ribs of my framework and the connecting keel belt.

20 Fig. 9 is a fragmentary outside elevational view of the gunwale portion of the frame of my boat and partially broken away to illustrate details of construction of my sectional gunwale.

25 Fig. 10 is a perspective view of the oar lock assembly for my boat.

30 My boat is most practical when manufactured in relatively small sizes for the use of fisherman and sportsman but its construction is adaptable to any size of boat. In the drawings I have illustrated a small rowboat arranged to carry two passengers and provided with a center seat 1 and stern seat 2. The boat consists of an outer shell or skin 3 secured over a collapsible framework 4 which is held in rigid shape when erected by a folding sectional keel 5 and sectional gunwales 6. Interleaved folding foot boards 7 are provided for the bottom of the boat and oar locks, generally indicated at 8, are arranged to receive oars for rowing the boat.

35 Considering first the construction of the framework of my boat attention is directed to Figs. 2, 3, 5 and 7 to 9. The principal body forming members of my framework are a series of U-shaped ribs 9, a curved stem or prow member 10 and a stern frame 11. The rib members vary in size to provide the desired shape to the boat. They are connected at their centers by a keel belt 12 of flexible character permanently secured by the rivets 13 to the bottom of each rib. The forward end of the belt 12 extends forwardly along the front of the stem 10 and is riveted thereto as at 14. The rear end of the belt 12 is carried upwardly and riveted to the cross member 15 of the stern frame 11.

The belt 12 is of flexible character so as to be easily collapsed permitting the several frame members to be nested in a small bundle. The belt 12 is relatively non-elastic so as to limit the spacing between the ribs in their erected position and I prefer to make the belt 12 of heavy fabric material.

The upper ends of the ribs 9 and stem 10 are connected by a gunwale belt 16 of flexible material similar to the keel belt 12. The gunwale belt 16 is of hollow tubular shape as is most clearly illustrated in Figs. 3 and 5 and has secured thereto the downwardly opening pockets 17 within which the upper ends of the ribs 9 are permanently secured by the rivets 18. The pockets 17 are conveniently secured to the gunwale belt 16 by stitching before the gunwale belt is sewed into tubular shape. The gunwale belt 16 extends continuously around the front of the stem 10 and is secured thereto by a strap or stirrup 19 (see Fig. 2). The rear ends of the gunwale belt 16 are folded around the back of the stern frame 11 and riveted thereto as at 20 (see Fig. 5) so as to provide an open end to each side of the tubular belt.

The stem member 10 of the framework is curved to provide a vertical prow portion and a generally horizontal keel extension 21 which extends rearwardly over the center of the forward rib member 9 when in erected position. The keel extension 21 carries a rearwardly opening channel bracket 22 arranged to receive the forward end of the sectional main keel 5 and the main keel is notched along the under side of its forward end to have a rabbeted engagement with the keel extension 21. The rear end of the keel extension 21 is longitudinally and vertically slotted as at 23 (see Fig. 2) to receive the bolt 24 carried by the forward section of the keel 5 to cooperate with the channel bracket 22 in preventing lateral displacement between the keel and stem 10.

The bottom cross member 15 of the rear frame 11 is provided with a forwardly opening channel bracket 25 arranged to receive the rear end of the keel 5. The rear end of the keel carries a depended lug 26 engageable with a slot in the lower flange of the channel bracket 25 to prevent lateral displacement of the keel member relative to the stern frame. I provide a pin on the forward end of the keel which is engageable in a hole in the web of the channel bracket to further interlock the keel and keel extension.

The upper cross member 27 of the stern frame pivotally supports the brace bars 28 which are arranged to be swung inwardly and connected to a bolt 29 by the wing nut 30 when the frame is erected. The angle braces 28 may be of wood or metal construction but I prefer to use wood braces with suitable metal attaching clips on each end thereof. The angle braces 28 are provided with brackets 31 on their inner sides which are arranged to engage and support the rear edge of the rear seat 2. The rear seat may thus be made of two panels hingedly connected with one of the panels notched to fit over the keel 5 as illustrated in Fig. 1.

The keel 5 is of the sectional jack-knife type having front and rear sections pivotally secured between the spaced side pieces of the center section 32 so that the keel may be folded into a short body. When the keel is extended in the framework in the manner illustrated in Fig. 2 it will stretch the keel belt 12 to taut position to prop-

erly locate the several frame members 9 and stem 10 and stern frame 11.

After the framework has been erected on the keel 5, sectional gunwale members 33 having a relatively thin, slat like shape are pressed or pushed through the openings in the rear of the gunwale tubes 16 as indicated by the dotted lines in Fig. 5. The rear ends of each slat 33 define vertical slots 34 for receiving inwardly turned flanges on the ends of the tongue clips 35 secured to the next succeeding section of the gunwale. A sufficient number of sections are pressed into each side of the gunwale tubes to form a complete gunwale along each side of the boat and complete the stiffening of the framework.

The cover or skin 3 for covering the framework is preferably made of water proof canvas or fabric of the desired weight and is shaped to fit the framework with sufficient material along the edges 20 of the skin to lap over the gunwales as at 36. A rear flap is provided at 37 and a pocket portion 38 is formed at the prow of the skin to fit over and receive the upper end of the stem 10. The side flaps 36 have eyelets or rings 39 securely 25 stitched thereto so that a lacing cord 40 may be passed through the eyelets and underneath lugs 41 secured to each of the ribs 5. The lacing cord 41 thus serves to stretch the skin tightly over the framework. The rear flap 37 is provided with 30 female snap fasteners designed to engage the lugs 42 secured to the inside of the upper cross member 27 of the stern frame. In order to stiffen the skin between the ribs of the framework I provide a series of longitudinal reinforcing slats 35 43 which I secure to the inside of the skin by stitching them inside of pockets 44. In order that the skin may be collapsed I divided the reinforcing slats 43 longitudinally in three sections as is most clearly illustrated at 45 in Figs. 1 and 6. The 40 longitudinal reinforcing slats 43 are of course shaped and located on the skin to conform to the shape of the boat and support the skin between the transverse ribs 9. When the skin is removed from the frame it may be folded and rolled transversely and further folded longitudinally along the division 45 between the sections of the longitudinal slats 43 to provide a small compact bundle.

In order to reinforce that portion of the skin lying between the ends of the sections of the slats 43 I provide reinforcing flaps 46 of canvas or other suitable fabric which I stitch to the skin 3 on one side of the folding sections 45. The flaps 46 are provided with short, longitudinally extending slats 47 which are stitched in pockets 48 on the flaps and arranged to lie between adjacent longitudinal slats 43 and bridge the folding section 45 of the skin. The slats 48 are long enough to have their ends supported by the two adjacent ribs 9 so that the skin is longitudinally supported throughout its entire length. In collapsing the skin the flaps 46 are folded away from the sections 45 of the skin so that the entire skin may be folded as previously described.

The oar locks 8 illustrated in Fig. 10 consist of an upper bar 49 which is secured to the gunwale by the U-shaped hooks 50. The upper bar 49 carries an angle fixture 51 on which the socket 52 is formed for receiving the pin of the oar. A bolt 53 extends downwardly from the upper bar 49 to a lower bar 54 arranged to engage the under side of any two adjacent lugs 41 on the rib members 9 to draw the oar lock tightly down on the gunwale. The ends of the lower bar 54 are notched as at 55 to fit between the adjacent ribs 9.

I have thus described a highly practical commercial embodiment of my boat and it should be understood that I intend this description as an example only and not as definitive of the limits of my invention. Obviously the details of the connections between my frame members and gunwale belts could be altered without departing from the theory of my invention and my framework could be used with a modified form of skin or the skin could be used on a modified form of framework.

Having thus described my invention what I claim as new and desire to secure by Letters Patent is:

1. A collapsible boat including a framework and a skin, said framework comprising a plurality of different sized U-shaped rib members, a rigid stern frame, a rearwardly curved stem, a keel belt of flexible relatively inelastic character permanently connected to the underside of the center of said ribs and the front of said stem and rear of said stern frame, a tubular flexible gunwale belt having pockets secured to the sides thereof, said pockets being permanently secured to the tops of said ribs, said belt being secured to said stem and said stern frame, interlocking sectional gunwale slats disposed in said gunwale belts and a folding keel member interlockingly engaging said stem and said stern frame to extend said keel belt and frame, said skin comprising a fabric body shaped to fit around said frame with flaps adapted to be wrapped over said gunwales, a plurality of longitudinal reinforcing slats stitched to the inside of said skin, said reinforcing slats being divided in longitudinal sections along transverse folding lines of said skin, and reinforcing flaps secured to said skin and arranged to fold across the folding lines of said skin in the erected position of said skin, said reinforcing flaps having short slats stitched therein to lie between adjacent reinforcing slats in said skin and bridge said folding sections of said skin between adjacent ribs of said framework.

2. A collapsible boat including a framework and a skin, said framework comprising a plurality of U-shaped rib members, a rigid stern frame, a rearwardly curved stem, a keel belt of flexible character permanently connected to the center of said ribs and the front of said stem and rear of said stern frame, tubular flexible gunwale belts permanently secured to the tops of said ribs, to said stem and to said stern frame, said tubular belts being open at the rear ends thereof, sectional gunwale slats disposed in said gunwale belts and being removable through the open ends of said belts, and a folding keel member interlockingly engaging said stem and said stern frame to extend said keel belt and frame, said skin comprising a fabric body shaped to fit around said frame, a plurality of longitudinal reinforcing slats secured to the inside of said skin, said reinforcing slats being divided in longitudinal sections along transverse folding lines of said body, and reinforcing flaps secured to said skin and arranged to fold across the folding lines of said body, said reinforcing flaps having other slats secured thereto to lie between adjacent reinforcing slats in said skin and bridge said folding sections of said body between adjacent ribs of said framework.

3. A collapsible boat including a framework and a skin, said framework comprising a plurality of U-shaped rib members, a rigid stern frame, a rearwardly curved stem, a keel belt of flexible character permanently connected to the center

of said ribs and the front of said stem and rear of said stern frame, tubular flexible gunwale belts permanently secured to the tops of said ribs, to said stem and to said stern frame, said tubular belts being open at the rear ends thereof, sectional gunwale slats disposed in said gunwale belts and being removable through the open ends of said belts, and a folding keel member interlockingly engaging said stem and said stern frame to extend said keel belt and frame, said skin comprising a fabric body shaped to fit around said frame and a plurality of longitudinal reinforcing slats secured to the inside of said skin, said reinforcing slats being divided in longitudinal sections along transverse folding lines of said body.

4. A collapsible boat including a framework and a skin, said framework comprising a plurality of U-shaped rib members, a stern frame, a stem, a keel belt of flexible character permanently connected to intermediate portions of said ribs and to said stem and to said stern frame, tubular flexible gunwale belts permanently secured to the tops of said ribs to said stem and to said stern frame, sectional gunwale slats disposed in said gunwale belts and a folding keel member interlockingly engaging said stem and said stern frame to extend said keel belt and frame, said skin comprising a fabric body shaped to fit around said frame, a plurality of longitudinal reinforcing slats secured to said skin, said reinforcing slats being divided in longitudinal sections along transverse folding lines of said body, and reinforcing flaps secured to said skin and arranged to fold across the folding lines of said body, said reinforcing flaps having other slats secured thereto to lie between adjacent reinforcing members in said skin and bridge said folding sections of said body between adjacent ribs of said framework.

5. A collapsible boat including a framework and a skin, said framework comprising a plurality of U-shaped rib members, a stern frame, a stem, a longitudinal belt of flexible character permanently connected to intermediate portions of said ribs and to said stem and to said stern frame, tubular flexible gunwale belts permanently secured to said ribs to said stem and to said stern frame, sectional gunwale slats disposed in said gunwale belts and a folding keel member interlockingly engaging said stem and said stern frame to extend said keel belt and frame, said skin comprising a fabric body shaped to fit around said frame and a plurality of longitudinal reinforcing slats secured to said skin, said reinforcing slats being divided in longitudinal sections along transverse folding lines of said body.

6. A frame for a collapsible boat comprising, a plurality of U-shaped ribs graduated in size to determine the shape of the boat, a stem having a rearwardly turned keel extension, a stern frame, a keel belt of non-elastic flexible material secured to the center of said ribs to determine the maximum spacing of said ribs, the rear of said keel belt being secured to the back of said stern frame, the front of said keel belt being secured to the front of said stem and arranged to underly said keel extension, non-elastic flexible gunwale belts of tubular construction extending along the tops of said ribs and stern frame and secured to said stem below the top thereof, pockets secured to the inside of said tubular belts and permanently receiving the upper ends of said ribs, the rear ends of said belt being secured to said stern frame and de-

fining openings thereat, sectional gunwale members having interlocking engagement between the sections thereof and positioned in said tubular belts, lugs projecting from the insides of said ribs below the tops thereof and adapted to engage a lacing cord to secure a skin to said frame, a vertically folding keel having interlocking engagement with said stern frame and the rear of said keel extension, and braces extending from the sides of said stern frame and removably secured to the top of said keel forwardly of said stern frame, said angle braces having shoulder portions adapted to support a seat in the stern of said frame.

7. A frame for a collapsible boat comprising, a plurality of U-shaped ribs graduated in size to determine the shape of the boat, a stem having a rearwardly turned keel extension, a stern frame, a keel belt of non-elastic flexible material secured to the center of said ribs to determine the maximum spacing of said ribs, the rear of said keel belt being secured to the back of said stern frame, the front of said keel belt being secured to the front of said stem and arranged to underly said keel extension, non-elastic flexible gunwale belts of tubular construction extending along the tops of said ribs and stern frame and secured to said stem below the top thereof, pockets secured to the inside of said tubular belts and permanently receiving the upper ends of said ribs, the rear ends of said belt being secured to said stern frame and defining openings thereat, sectional gunwale members having interlocking engagement between the sections thereof and positioned in said tubular belts, a vertically folding keel having interlocking engagement with said stern frame and the rear of said keel extension, and braces extending from the sides of said stern frame and removably secured to the top of said keel forwardly of said stern frame.

8. A frame for a collapsible boat comprising, a plurality of U-shaped ribs graduated in size to determine the shape of the boat, a stem having a rearwardly turned keel extension, a stern frame, a keel belt of non-elastic flexible material secured to said ribs to determine the maximum spacing of said ribs, the rear of said keel belt being secured to said stern frame, the front of said keel belt being secured to said stem, a flexible gunwale belt of tubular construction extending along the tops of said ribs and stern frame, and secured to said stem, pockets secured to said tubular belt and receiving the upper ends of said ribs, the rear ends of said belt being secured to said stern frame, sectional gunwale members having interlocking engagement between the sections thereof and removably positioned in said tubular belt and a folding keel having interlocking engagement with said stern frame and the rear of said keel extension.

9. A frame for a collapsible boat comprising, a plurality of U-shaped ribs, a stem having a rearwardly turned keel extension, a stern frame, a plurality of belts of flexible material secured to said ribs to determine the maximum spacing of said ribs, the rear of said belts being secured to said stern frame, the front of said belts being secured to said stem, one of said belts being of tubular construction, one end of said tubular belt defining an opening thereto and a sectional longitudinal stiffening member having interlocking

engagement between the sections thereof and removably positioned in said tubular belt.

10. A skin for covering the frame of a collapsible boat comprising a body of waterproof fabric shaped to conform to the shape of said frame, a pocket formed at the top of the prow of said body and arranged to receive the stem of said frame, a plurality of transversely spaced longitudinally extending pocket forming pieces stitched to the inside of said body, said pocket forming pieces being divided into longitudinal sections along transverse folding lines of said body, sectional longitudinal slats permanently secured in said pocket forming members, reinforcing flaps secured to the inside of said body and arranged to be folded across the folding lines thereof, reinforcing slats permanently stitched in said reinforcing flaps and arranged to lie between transversely adjacent slats in said body and bridge the space between adjacent longitudinal sections of said longitudinal slats.

11. A skin for covering the frame of a collapsible boat comprising a body of fabric shaped to conform to the shape of said frame, a plurality of transversely spaced longitudinally extending pocket forming pieces secured to the inside of said body, said pocket forming pieces being divided into longitudinal sections along transverse folding lines of said body, sectional longitudinal slats secured in said pocket forming members, reinforcing flaps secured to the inside of said body and arranged to be folded across the folding lines thereof, reinforcing slats secured in said reinforcing flaps and arranged to lie between transversely adjacent slats in said body and bridge the space between adjacent longitudinal sections of said longitudinal slats.

12. A skin for covering the frame of a collapsible boat comprising a body of waterproof sheet material shaped to conform to the shape of said frame, a plurality of transversely spaced longitudinally extending pocket forming pieces secured to said body, said pocket forming pieces being divided into longitudinal sections along transverse folding lines of said body, sectional longitudinal slats secured in said pocket forming members, reinforcing flaps secured to the inside of said body and arranged to be folded across the folding lines thereof, reinforcing slats secured in said reinforcing flaps and arranged to lie between transversely adjacent slats in said body and bridge the space between adjacent longitudinal sections of said longitudinal slats.
